GEORGE G. FLOYD, OF CHICAGO, ILLINOIS, ASSIGNEE TO AMERICAN STEEL FOUNDRIES,
OF CHICAGO, ILLINOIS, A CORPORATION OF NEW JERSEY.

DRAFT MECHANISM.

Application filed March 5, 1919. Serial No. 230,733.

To all whom it may concern:

Be it known that I, GEORGE G. FLOYD, a citizen of the United States, residing at Chicago, in the county of Cook and State of Illinois, have invented certain new and useful Improvements in Draft Mechanism, of which the following is a specification.

This invention relates to draft mechanism and more particularly to draw bar yoke mechanism.

It is common practice to connect the rear end of a draw bar to the draw bar yoke by a plurality of rivets. These rivets of necessity must be quite long. The use of rivets for connecting the draw bar and draw bar yoke is quite unsatisfactory. In the first place, it is very difficult to upset a rivet of the necessary length and at the same time fill the rivet holes thoroughly. In the second place, it is quite impossible to upset a rivet of the necessary length for the reason that the rivet merely bends in its unsupported portions within the hollow draw bar. Such being the case poor riveting results, the rivets promptly becoming loose, wearing badly and, due to the fact that the middle portions of the rivets are unsupported, the rivets bend as the result of the work required of them and eventually their heads are pulled off, rendering the rivets useless.

Another disadvantage in using rivets is that the yoke and draw bar are permanently secured together, necessitating the removal of the entire draft gear when it is desired to remove the coupler, the yoke, or re-rivet the yoke to the coupler.

To overcome some of these disadvantages, instead of using two rivets a flat key has been used to connect the draw bar and draw bar yoke, the width of the key being substantially the diameter of the rivets used and the breadth of the key being such as occupied by the rivets and in addition thereto the space therebetween. In retaining this flat key in place it has been the practice to provide said key with a head at the upper end thereof so that the weight of the key rests upon the head, the lower end of the key being provided with a cotter pin or bolt to prevent displacement of the key. However, having the head on top as heretofore used, means that the coupler and yoke and draft gear necessarily must be taken down as a unit to renew the coupler. This is undesir-

able, for in most instances, the only part which requires repair is the coupler. A great many small repair points along railroad lines can make repairs to replace couplers quickly but it doubles or triples the work and the time required if the whole draft gear must be taken down to renew a coupler.

Accordingly, one object of my invention is to make it possible to readily assemble and disassemble the draw bar and draw bar yoke in their normal positions to facilitate repair of the parts in question.

Another object is to provide a simple, novel and efficient connection between a draw bar and draw bar yoke adapted to meet all of the requirements under service conditions.

A further object is to provide a key connection for draw bars and yokes whereby the key may be applied to and removed from operative position from below the draft mechanism without having to take the whole mechanism down, and to provide means for maintaining the key in operative position.

These and other objects are accomplished by means of the arrangement shown on the accompanying sheet of drawings in which—

Figure 1 is a top plan view of the draw bar and draw bar yoke connected by my novel connecting means;

Figure 2 is a longitudinal sectional view of the same parts, the connecting means being shown in side elevation;

Figure 3 is a sectional view taken in the plane of line 3—3 of Figure 2; and

Figure 4 is a sectional view showing a modified form of connecting means.

Referring to the figures of the drawings, it will be noted that I have shown a draw bar 10 and a draw bar yoke having an upper arm 11 and a lower arm 12, said draw bar 10 and yoke arms 11 and 12 having vertically arranged registering openings 13, 14 and 15, respectively, for the reception of the connecting means between the draw bar 10 and the draw bar yoke arms 11 and 12.

As mentioned above it is desirable for the weight of the key to be suspended from the head at its upper end, but at the same time it is undesirable to provide the key with such a head at the upper end which will require complete removal of the entire draft gear when it is desired only to replace the

draw bar. As a matter of fact, it is quite necessary that the upper end of the key be provided with some sort of head or enlargement to prevent the upper end of the key 5 from being drawn under the upper yoke arm as the result of pulling strains, for it is readily apparent that if there was no head at the upper end of the key there would be a tendency for the top arm of the yoke to 10 slip over the top of the key.

In solving this problem, taking advantage 15 of all of the bad features, I have provided a fabricated connection between the draw bar and draw bar yoke including three vertically and adjacently arranged members 16, 17 and 18, the member 16 being the key proper and being interposed between the members 17 and 18 which I choose to call fillers. The key 16, as will be observed from Figures 1 20 and 2 is in the form of a bulb beam, the beam being I-shaped in section, generally speaking. The enlarged or bulb portions 19 of the beam are substantially the same width as the registering openings 13, 14 and 15, 25 the web portions 20 of the key being reduced sufficiently to permit the reception of the filler members 17 and 18 within said registering openings, it being understood that filler members 17 and 18 occupy portions 30 of the openings directly adjacent the web portion 20 of the key. The lower ends of the key 16 and filler members 17 and 18 are provided with transverse registering openings for the reception of a bolt 21 for holding 35 the three members or fabricated structure together, the bolt being provided with a nut 22 and cotter pin or other suitable key 23.

It will be noted that the upper ends of the 40 filler members 17 and 18 are provided with laterally extending head portions 24 and 25 respectively, whereby the key in effect is provided with a head for engaging cooperating shoulders 26 and 27 respectively, 45 formed in a recess 34 in the upper arm 11 of the draw bar yoke for supporting the key. The filler members 17 and 18 also are provided with laterally extending projections 28 and 29 respectively, which may cooperate 50 with shoulders 30 and 31 respectively, formed in a recess 35 in the lower arm 12 of the draw bar yoke. These heads prevent the key from being drawn to the inside portions of the draw bar yoke arms 11 and 12, 55 and thereby provide a connection between the draw bar yoke and draw bar which is effective at all times.

In assembling the parts either one of the 60 filler members 17 or 18 may be set in place as shown in Figure 3, then the other filler member is set in place as shown in said figure and then the key is inserted between the filler members 17 and 18 and the bolt 21 passed through the lower ends of all of said 65 members to connect the same together, there-

by forming a strong connection between the draw bar and draw bar yoke, which at the same time permits ready assemble and disassemble of the parts in question, the weight of the fabricated structure being sustained 70 by the head portions 24 and 25.

It is realized that no matter how tight bolts may be set and no matter if split keys are used in connection with bolts and nuts, there is always a chance for the nuts and 75 keys to become loosened and displaced, sometimes resulting in the accidental removal of bolts. Assuming that the bolt 21 is apt to be accidentally displaced from its normal position to permit the key 16 to fall out of 80 position and thereby cause the draw bar and draw bar yoke to become disconnected, I have shown a modified form, illustrated in Figure 4, which will overcome this undesirable feature. In this connection when the 85 filler members 17 and 18 are set in place the lower ends thereof are bent into the position shown by dotted lines in Figure 4, it being noted that the lower ends of said filler members are provided with inwardly extending 90 projections 32 and 33, respectively. After the key 16 is set in place the bolt 21 may be passed through the enlarged openings in the filler members, and also through the registering opening of the key 16, whereupon the nut 22 may be drawn up to such an extent that the inner sides of the lower portions of the filler members 17 and 18 actually engage the sides of the key 16 in which case the inwardly extending projections 32 and 33 underlie the key 16. It has been ascertained as a result of experiment that when 95 the lower ends of the filler members are drawn from the position shown by dotted lines in Figure 4 to the position shown in full lines in Figure 4 by the use of a one inch bolt and a nut, the projection 32 will still underlie the key 16 a sufficient amount to prevent the key from dropping, even though the bolt 21 is removed, thereby providing a 100 doubly safe arrangement.

It is my intention to cover all modifications of the invention falling within the spirit and scope of the following claims.

I claim:

1. In draft mechanism, a draw bar and a draw bar yoke having registering openings, means for connecting the draw bar and yoke, said means including a key of I-shaped conformation fitting within said openings, and 115 filler members mounted adjacent to the web portion of said key on the two sides thereof, the planes of separation between the web portion of said key and said members lying longitudinally of said draw bar and yoke, 120 said members each having a shouldered portion in engagement with said yoke at the top and bottom thereof for holding purposes, said members having portions extending beyond certain of said shouldered por- 125 130

tions, and means mounted in said extending portions for connecting said key and members.

2. In draft mechanism, a draw bar and a draw bar yoke having registering openings, means for connecting the draw bar and yoke, said means including a key of I-shaped conformation fitting within said openings, and filler members mounted adjacent to the web portion of said key on the two sides thereof, the planes of separation between the web portion of said key and said members lying longitudinally of said draw bar and yoke, said members each having a shouldered portion in engagement with said yoke at the top and bottom thereof for holding purposes, said members having portions extending beyond certain of said shouldered portions, and means mounted in said extending portions for connecting said key and members, said extending portionslapping over said end.
3. In draft mechanism, in combination with a draw bar, a draw bar yoke having vertically registering openings, means for connecting said draw bar and said yoke, said means including a key and a member mounted alongside of said key, said member having shouldered portions in engagement with said yoke at the top and bottom thereof for holding functions, said member being provided with a portion extending beyond one of said shouldered portions, and means extending through said key and extending portion for holding said key and member against relative movement, said key and member being separated along a surface extending longitudinally of said draw bar and yoke.
4. In draft mechanism, in combination

with a draw bar, a draw bar yoke having vertically registering openings, means for connecting said draw bar and said yoke, said means including a key and members mounted alongside of said key on the two sides thereof, the planes of separation between said key and said members extending longitudinally of said draw bar and yoke, said members having shouldered portions in engagement with said yoke at the top and bottom thereof for holding functions, each of said members being provided with a portion extending beyond certain of said shouldered portions, and means extending through said key and extending portions for holding said key and members against relative movement.

5. In draft mechanism, in combination with a draw bar, a draw bar yoke having vertically registering openings, means for connecting said draw bar and said yoke, said means including a key and members mounted alongside of said key on the two sides thereof, the planes of separation between said key and said members extending longitudinally of said draw bar and yoke, said members having shouldered portions in engagement with said yoke at the top and bottom thereof for holding functions, each of said members being provided with a portion extending beyond certain of said shouldered portions, and means extending through said key and extending portions for holding said key and members against relative movement, said extending portions having parts projecting beyond the end of said key and lapped over said end.

Signed at Chicago, Illinois, this 19th day of February, 1919.

GEORGE G. FLOYD.
